US00D758102S

(12) **United States Design Patent**
Mason

(10) **Patent No.:** **US D758,102 S**
(45) **Date of Patent:** **** Jun. 7, 2016**

(54) **CUSHION**

(71) Applicant: **Matteo Mason**, Limena (IT)

(72) Inventor: **Matteo Mason**, Limena (IT)

(73) Assignee: **Technogel Italia S.R.L.** (IT)

(**) Term: **15 Years**

(21) Appl. No.: **29/531,275**

(22) Filed: **Jun. 24, 2015**

(30) **Foreign Application Priority Data**

Dec. 30, 2014 (EP) 00267432-0001
Dec. 30, 2014 (EP) 002607432-0006
